CLAIM

The ornamental design for an acupressure pillow as shown and described.

DESCRIPTION

1.1 : Perspective

1.2 : Front

1.3 : Back

1.4 : Left

1.5 : Right

1.6 : Top

1.7 : Bottom

2.1 : Perspective

2.2 : Front

2.3 : Back

2.4 : Left

2.5 : Right

2.6 : Top

2.7 : Bottom

3.1 : Perspective

3.2 : Front

3.3 : Back

3.4 : Left

3.5 : Right

3.6 : Top

3.7 : Bottom

Description of the Reproduction(s): figs. 1.1, 2.1 and 3.1: perspective views; figs. 1.2, 2.2 and 3.2: front views; figs. 1.3 2.3 and 3.3: back views; figs. 1.4, 2.4 and 3.4: left views; figs. 1.5, 2.5 and 3.5: right views; figs. 1.6, 2.6 and 3.6: top views; figs. 1.7, 2.7 and 3.7: bottom views.
